US00D465623S

(12) **United States Design Patent** (10) Patent No.: **US D465,623 S**
Main et al. (45) Date of Patent: **** Nov. 12, 2002**

(54) **VACUUM CLEANER**

(75) Inventors: **Stacey Main**, Baltimore, MD (US);
Gabriel Concarri, Eldersburg, MD
(US); **Mark Stratford**, Darlington
(GB); **Michael Waldron**, County
Durham (GB)

(73) Assignee: **Black & Decker Inc.**, Newark, DE
(US)

(**) Term: **14 Years**

(21) Appl. No.: **29/143,675**

(22) Filed: **Jun. 18, 2001**

(51) LOC (7) Cl. **15-05**

(52) U.S. Cl. **D32/22**

(58) Field of Search D32/21-22, 25,
D32/31, 34; 15/329, 320-321, 323, 350-353
